United States Patent Office

Des. 183,540

Patented Sept. 16, 1958

183,540

COMBINED CAMERA AND FLASH GUN

Joseph Palma, Jr., Wheaton, Ill.

Application June 10, 1957, Serial No. 46,540

Term of patent 14 years

(Cl. D61—1)

FIG. 1

FIG. 2

FIG. 3

FIG. 4

FIG. 5

Fig. 1 is a perspective view in closed position of a combined camera and flash gun, showing my new design;

Fig. 2 is a perspective view in open position;

Fig. 3 is a rear-elevational view;

Fig. 4 is a side elevational view, the opposite side having substantially the same appearance; and

Fig. 5 is a bottom plan view thereof.

I claim:

The ornamental design for a combined camera and flash gun, as shown and described.
